FIG. 2

FIG. 1

FIG. 3

FIG. 5

FIG. 4

FIG. 1 is a side elevational view of a hair dryer showing my design, the obverse side being identical.

FIG. 2 is a top plan view.

FIG. 3 is an elevational view taken from the right of FIG. 1.

FIG. 4 is an elevational view taken from the left of FIG. 1.

FIG. 5 is an enlarged fragmentary view similar to FIG. 1.

The conventional power cord in the figures is shown fragmentarily for ease of illustration.

I claim:

The ornamental design for a hair dryer, substantially as shown and described.
